RAKER SHARPENING GAUGE

Jay C. Stone, Clayton, Wash.

Application May 24, 1946, Serial No. 672,036

3 Claims. (Cl. 76—46)

1

This invention relates to a raker sharpening gauge for use when sharpening narrow saws of the type known as Swedish buck saws and it is one object of the invention to provide a gauge by use of which teeth of a saw may be accurately filed and swaged.

Another object of the invention is to provide a gauge so formed that it may be very easily adjusted to dispose a file and saw blade in proper angular relation to each other.

Another object of the invention is to provide the device with a swage so located that the teeth of a saw may be accurately bent when setting the teeth of the saw.

Another object of the invention is to provide a gauge with a guide plate carried by a support so formed and mounted that it may be very easily adjusted and accurately set by a workman having little experience in filing saws.

The invention is illustrated in the accompanying drawings wherein:

Fig. 1 is a side elevation of the improved gauge.

Fig. 2 is a top plan view of the device.

Fig. 3 is a sectional view upon an enlarged scale taken transversely through the gauge along line 3—3 of Figure 1.

Fig. 4 is an end view of the gauge.

This improved gauge has a main frame 1 formed with a side wall 2 from the lower edge of which projects a base flange 3. Lugs 4 project laterally from the upper edge of the side wall over the base flange 3 and upon these lugs or tongues rest front and rear cap plates 5 and 6 which are firmly secured by screws 7. Midway its length the side wall is formed with an elongated recess 8 and under this recess the wall is formed with an opening 9 located close to the lower edge of the wall. Tongues 10 project horizontally from the wall 2 over openings 11 and at the upper edge of the opening 9 is a tongue 12 formed with an opening 13 aligned with an opening 14 formed through the flange midway the length thereof. Abutment tongues 15 extend downwardly from the cap plates in spaced relation to their inner ends.

A bridging bar or block 16 extends longitudinally of the frame 1 within the length of the recess 8 and this bar has upstanding arms 17 at its ends from which project feet 18 carrying upstanding pins 19 which pass through openings formed in the inner end portions of the cap plates 5 and 6. A shank 20 extends downwardly midway the length of the block or bridge bar 16 and through this shank and the mid-portion 16 is formed a threaded opening 21 to

2

receive the threaded upper portion of the adjusting bolt 22. The upper portion of the bolt is formed with fine threads which are preferably thirty-two to the inch and each time the bolt is turned the bridge bar will be shifted vertically one thirty-second of an inch for each complete rotation of the bolt. An offset portion 23 projects from the side plate 2 midway its length and in this offset portion is formed a vertically extending groove 24 into which fits a rib 25 projecting from the shank and serving to guide vertical movement of the bridge bar. The bolt rotatably passes through the openings 13 and 14 of the tongue 12 and flange 3 and about the bolt is mounted a collar 26 which is located between the tongue and the flange and secured by a set screw 27 so that it turns with the bolt. Gauge marks 28 are provided upon the edge faces of the tongue and the flange, and by watching the graduations 29 of the collar pass the marks 28 the number of turns imparted to the bolt when vertically adjusting the bridge bar may be ascertained. The bolt is held against vertical movement by the collar and the lower portion of the bolt which is firmly secured after the bridge bar has been moved vertically to an adjusted position.

The bridge bar or block supports a guide plate 32 disposed at an incline and having depending tongues or lugs 33 which are secured against the bridge bar by screws 34. The plate extends at a downward incline towards the cap plate 5 and is of such length that it may move vertically without striking the cap plates. The width of the plate is such that its outer side edge is flush with the outer side edges of the cap plates and the outer side portion of the plate is formed with slots leading from its ends and forming the plate with a strip 35 connected with the main portion of the plate by a neck or tongue 36. A tongue 37 projects from the shank 20 of the bridge bar under the plate 32 and is formed with a threaded opening through which passes a screw 38 having a turning head at its lower end so that it may be grasped and turned to move it upwardly into position to engage the under face of a file and bind the file against lower ends of the abutment tongue 15. A post 39 projects upwardly from the end of plate 32 near the inner end of the cap plate 5 and this post carries a sleeve 40 formed with a vertically extending threaded bore to receive the swaging screw 41 which has its lower end passing through an opening formed in the inner portion of the cap plate 5 and above the sleeve carries a locking nut 42 for engaging the

upper end of the sleeve and securing the swaging screw in an adjusted position.

The operation is as follows:

When jointing the cutting teeth of a saw blade, a file is mounted beneath the abutting tongues 15 and held in position by the screw 38, the file extending in the path of the teeth as shown in dotted lines Fig. 4. The guage is then placed against the saw blade, by permitting the base 3 and tongue 37 to contact the blade. The teeth are then permitted to contact the file and by moving the guage along the saw blade, the jointing is completed. After jointing the saw, the cutting teeth are filed in the usual manner.

When filing the raker teeth, the file is removed from the guage and the teeth of the saw are placed into the slots 32' of block 32. Adjusting screw 29 is then set for the proper depth to be filed. After the filing is completed the guage is then moved over and the raker point struck with a hammer in order to swedge the raker teeth to the desired angle.

Having thus described the invention, what is claimed is:

1. A device of the character described comprising a main frame having a vertically disposed side plate and a flange projecting laterally along its lower edge, front and rear cap plates projecting laterally from the upper edge of the side plate of said frame over the side flange and having their inner ends spaced from each other, the side plate being formed with a recess in its upper portion, between the cap plates and with an opening in its lower portion under the recess, there being a vertical track in the side plate between the recess and the opening, a removable bridge bar extending between said cap plates and shiftable vertically in the track and having its ends extending under the cap plates and provided with upstanding pins slidably passing through openings in the cap plates, a guide plate for a file extending at a longitudinal incline between the cap plates and secured to the bridge plate, lugs extending downwardly from said cap plates adjacent ends of said bridge bars and constituting seats for a file, a side arm for said bridge bar, a set screw threaded vertically through the side arm for binding a file against said lugs, an adjusting bolt passing vertically through the lower flange of the side plate and having its upper portion threaded and passing through a threaded opening formed vertically through the bridge bar for supporting the bridge bar and vertically adjusting the bar when the bolt is turned, an internally threaded sleeve over the inner end portion of one cap plate, and a swaging screw threaded vertically through said sleeve and having its lower portion passing through the cap plate.

2. A device of the character described comprising a main frame having a side flange along its lower edge, cap plates extending from front and rear portions of the upper edge of the main frame

and having inner ends spaced from each other, abutments extending downwardly from the cap plates and spaced from inner ends thereof, a bridging bar extending between said cap plates and under inner ends thereof, a bolt rotatably mounted vertically through the side flange of said frame and having its upper portion threaded through the bridging bar for supporting the bar against under faces of the cap plates, a side arm for said bridging bar, a set screw threaded vertically through the side arm for engaging a file and clamping the file against said abutments, a guide plate extending longitudinally at an incline between the cap plates and secured to the bridging bar, a sleeve over the inner end portion of the front cap plate, and a swaging screw threaded vertically through said sleeve with its lower portion passing through an opening in the front cap plate.

3. A device of the character described comprising a frame, front and rear cap plates projecting laterally of the frame, a bridge between the cap plates formed with a vertically extending bore, upper and lower side extensions for the frame having openings aligned with the bore, an adjusting screw extending vertically and rotatably mounted through the openings and having its upper portion threaded through the bore, a collar about said bolt removably secured thereon between the side extensions with its ends engaging the side extensions and preventing vertical movement of the bolt, the bolt when turned shifting the bridge to vertically adjusted positions, a nut threaded upon the bolt under the lower side extension for engaging the under face of the said lower side extension and securing the bolt in an adjusted position, a guide plate carried by said bridge and extending at a longitudinal incline between the cap plates, a swage carried by said guide plate and extending vertically in advance of the front end thereof, and means for mounting a file longitudinally of the frame under the guide plate and the cap plates.
